UNITED STATES PATENT OFFICE.

FRANK E. COWLES, OF WESTFIELD, MASSACHUSETTS.

WHIP.

SPECIFICATION forming part of Letters Patent No. 783,400, dated February 21, 1905.

Application filed November 12, 1903. Serial No. 180,865.

To all whom it may concern:

Be it known that I, FRANK E. COWLES, a citizen of the United States of America, residing at Westfield, in the county of Hampden and State 5 of Massachusetts, have invented new and useful Improvements in Whips, of which the following is a specification.

My invention relates to whips, and to that class thereof having a stock consisting of the 10 usual flexible sidings of ratan or similar material and a center or core of rawhide or other like tough and springy material, which center extends from or near the tip of the stock through the latter and somewhat beyond the 15 butt-end thereof.

The object of this invention is to provide in a whip of this class an improved tubular load-piece for receiving therein the butt-end of the whip-stock, which permits of verifying visually 20 the kind of material constituting the whip-core, and to provide in a load-piece such structural form as facilitates the application of a continuous plaited covering for the whip extending from the tip thereof over the stock 25 and said load-piece to a point somewhat below the lower extremity thereof, and means for so securing the parts of said plaited covering which extend beyond the part of said load-piece at the junction thereof with its reduced lower extremity that the ornamental 30 appearance of the whip is improved. I attain this object by means of the whip construction illustrated in the accompanying drawings, in which—

Figure 1 is a longitudinal sectional view of the whip-load, showing the lower portion of the whip-stock therein, the lower end of the core extending through a perforation in the lower end of the load. Fig. 2 is a longitudinal sectional view of the whip-load separate from the whip. Fig. 3 is a lower end view of the parts shown in Fig. 2. Fig. 4 is a side view of the lower portion of the complete plaited whip-stock, showing the bottom cap 45 in cross-section in place on the reduced lower end of the load-piece, the lower end of the whip-center projecting through said cap, and the latter shown as inclosing the extremities of the cover-threads and holding the same 50 tightly in that position.

Similar letters refer to like parts in the several figures of the drawings.

The load-piece *a* shown in Fig. 2 apart from the whip-stock *D* in longitudinal section has, as there shown, a tapering form exteriorly, 55 whereby its outer surface is adapted to coincide substantially with the general taper of the completed whip. (Shown in Fig. 4.) The lower end of said load-piece terminates in the part *b* thereof, of a diameter less than that of the part directly above it, thereby forming a shoulder *o*. Said part *b* may, if preferred, be screw-threaded to receive an ornamental cap *c*, adapted to be screwed thereon, or said part *b* may be left plain, as shown, and the 60 cap may have a smooth interior surface and be so fitted as to slide so closely onto said extremity that it will serve the purpose below set forth and keep its place on the butt, as is usual with similar parts of a whip. 70

Heretofore it has been the practice to so stock a whip that no parts of it contained within the sidings thereof were visible excepting at the extreme upper end or "tip" of the stock, and therefore to provide visible 75 means for determining the structure of the interior of the whip at the butt thereof the lower end of said load-piece has the central perforation *d*, through which the lower end of the whip-core *E* extends, as shown in Figs. 80 1 and 4.

The aforesaid tapering form is given to the load-piece *a* as aforesaid more especially to provide an outer surface for the stock between its extremities in such a continuous plane as 85 is desirable for receiving the plaited covering thereof, as shown in Fig. 4. Said covering, as shown, extends over said load-piece, the end *f* of the threads constituting the same being extended slightly over the surface of 90 said part *b*, as aforesaid, and there secured by said cap *c*, as above described, the latter having a central perforation through which the lower extremity of said core *E* may extend, as shown in Fig. 4. 95

It is obvious that a serviceable whip may be made embodying simply the structural elements shown in Fig. 1, and the cap *c*, if desired, protecting the exterior surface of the whip by any suitable varnish and extending 100

the lower end of the load-piece full size instead of reducing the diameter thereof, as shown, and securing the stock into the load-piece by the use of any suitable cement or

5 other well-known efficient means.

Having thus described my invention, what I claim, and desire to secure by Letters Patent of the United States, is—

1. A tubular metallic load-piece for whips 10 having a bottom in which is a centrally-located passage through which a part of the whip may extend, and having the outer diameter of the lower extremity thereof so reduced for a certain distance upward as to form a 15 shoulder *o* thereon.

2. A tubular metallic load-piece for whips having a bottom in which is a centrally-located passage through which a part of the whip may extend, and having the outer diameter of the lower extremity thereof so reduced 20

for a certain distance upward as to form a shoulder *o* thereon, and a braid-holding cap fitting said extremity and adapted to abut said shoulder.

3. A whip comprising a stock D and a central core E of tough flexible material, one extremity of which extends beyond the butt of said stock, and a tubular metallic load-piece receiving said butt and having a bottom in which is a passage through which said core 30 extremity extends in full view, a braided covering on said stock and load-piece, one end extending beyond the shoulder *o* of said load-piece and the cap *f* engaging the lower extremity of said covering and holding the same 35 against displacement.

FRANK E. COWLES.
